UNITED STATES PATENT OFFICE

HORACE A. STUKES, OF SAN ANTONIO, TEXAS

DESIGN FOR A FUEL FEEDING TANK

Application filed May 21, 1932. Serial No. 43,862. Term of patent 14 years.

To all whom it may concern:

Be it known that I, HORACE A. STUKES, a citizen of the United States, residing at San Antonio, in the county of Bexar, State of Texas, have invented a new, original, and ornamental Design for Fuel Feeding Tank, of which the following is a specification, reference being had to the accompanying drawing, showing the parts thereof.

Figure 1 is a front elevational view of the tank showing my new design, looking down from the top, on a reduced scale; and

Figure 2 shows a perspective view looking down from the top.

I claim:

The ornamental design for a fuel feeding tank as shown.

HORACE A. STUKES.
